UNITED STATES PATENT OFFICE.

ALFRED ERNST, OF PITTSBURG, PENNSYLVANIA, ASSIGNOR TO THE COAL AND COKE BY-PRODUCTS COMPANY, A CORPORATION OF WEST VIRGINIA.

CENTRIFUGAL DRY COAL-SEPARATOR.

942,251.

Specification of Letters Patent. Patented Dec. 7, 1909.

Application filed October 3, 1908. Serial No. 455,991.

To all whom it may concern:

Be it known that I, ALFRED ERNST, a citizen of the United States, residing at Pittsburgh, Pennsylvania, have invented certain new and useful Improvements in Centrifugal Dry Coal-Separators, of which the following is a specification, accompanied by drawings.

Although primarily designed as a centrifugal dry separator, the invention is obviously neither restricted necessarily to a dry process of separating, nor is it limited in its application to the separation of coal from slate and refuse.

The object of the invention is to combine a satisfactory degree of accuracy in separation with a good capacity, and as the invention is of a very simple nature it will be readily understood from the accompanying drawings which illustrate the form in which I prefer to use it.

In the drawings Figure 1 is a plan view, the left-hand half being an outside plan view and the right-hand half a view of the rotary separating table and the peripheral receiving chute for the slate and refuse. Fig. 2 is a central vertical section.

The preferred form of the apparatus illustrated comprises an inner stationary support B in which is journaled the vertical shaft C driven by the pulley D and carrying at its upper end the rotary centrifugal table F. Ball-bearings for carrying the weight-rotating parts are illustrated. The table F consists of an inner member G onto which the coal to be separated is delivered through the stationary chute H and from which the coal is discharged tangentially by the centrifugal force across the annular interval or intervals J. Beyond and outside of the intervals J is the receiving member or surface F of the table which I prefer to have consist of a horizontal portion F' and the rising or inclined portion F''. The receiving edge of the surface F' should be slightly lower than the surface G if moderate speeds of rotation are employed, but with very high speeds the difference between the level of the inner and outer members of the table on the respective sides of the interval J may be *nil*, as the centrifugal force will throw the slate with hardly any appreciable drop in crossing the interval. Beneath the table the inner and outer surfaces are preferably connected and united by the

spider arms K, which may be cast in one piece with the rest of the table.

At L is an annular air blast nozzle supplied by the air pipe M, the mouth of which directs the blast downward through the interval J at an inclination toward the vertical axis or shaft C so as to facilitate the separation of the lighter particles from the heavier by their being carried down through the interval J. Beneath the interval J is the coal chute N which is also annular in form and is inclined and convergent to the discharge mouth or chute P. Arranged peripherally of the outer member F is the delivery chute Q for the slate or heavier particles to be separated. This is also annular, inclined, and convergent to a delivery chute R.

The operation of the machine will be evident to those familiar with the art. The arrow T shows the tangential tendency of the heaviest particles and the arrow U shows the way in which after being received on the surface F they slide upward and are thrown off into the chute Q. The arrow V shows the approximate direction of the air blast, and it will be understood that the lighter particles follow trajectories and are delivered in various directions between those of the arrows V and T and passing downward through the interval J are received in the coal chute N. On delivering the mixed coal and slate to the chute H it passes down to the center of the table and there, receiving a gravitating movement from the table it is thrown outward by the centrifugal force, passing more or less radially over the interval J. The air friction combined with the downwardly directed air blast and the action of gravity, cause the specifically lighter substances of the same size to be separated from the heavy, and the smaller particles, which are more easily influenced by the air blast whether of the same or different substance from the heavier particles, to be carried through the interval into the coal chute. For this reason it is desirable that the coal be screened before using the separator, as the separation of particles of the same size and of different specific gravities will be more perfect than where there are not only differences of specific gravity but also great difference in size of the particles to be separated. The apparatus can, however, be used for separating fine and coarse

sizes of the same substance upon principles well understood in hydraulic and air separators.

I make no claim to having discovered any new principle of nature. On the contrary, I claim and desire to secure by Letters Patent for the purposes described, the following:

1. A rotary separator comprising a shaft 10 vertically mounted, a rotary table thereon having an inner and an outer member separated by an interval and each adapted to receive the material and discharge it therefrom by centrifugal force, said outer member 15 having a rising or inclined portion surrounding a horizontal receiving surface approximately in the same plane or level as that of the discharging edge of the inner member, for receiving the heavier material 20 discharged across said interval by centrifugal force, means for delivering material to be separated to the inner member, and means for catching or receiving the materials discharged from the outer member, for substantially 25 the purposes set forth.

2. A rotary separator comprising a shaft vertically mounted, a rotary table thereon having an inner and an outer member separated by an interval and each adapted to receive the material and discharge it therefrom by centrifugal force, said outer member having a receiving surface approximately in the same plane or level as that of the discharging edge of the inner member, 30 for receiving the heavier material discharged across said interval by centrifugal force, means for delivering material to be separated to the inner member, and means for catching

or receiving the materials discharged from the outer member, and a blast nozzle directed toward said interval, for substantially 40 the purposes set forth.

3. A rotary separating table having a vertical shaft and an inner member from which the material to be separated is thrown by 45 the centrifugal force, and having an outer rotary member presenting a comparatively thin edge which is located in approximately the same horizontal plane with the delivering edge of the inner member but at an interval therefrom to divide the material or 50 materials.

4. A rotary separating table having an inner member from which the material to be separated is thrown by the centrifugal force, 55 and having an outer rotary member presenting a comparatively thin edge which is located in position to divide the material or materials, and a blast duct having a mouth which restricts and directs a blast through 60 the interval between the inner and outer member.

5. A rotary separating table comprising two members in approximately a single horizontal plane with one or more separating intervals between them, and an air blast duct 65 provided with a mouth or mouths directed toward said interval or intervals.

In testimony whereof I have signed this specification in the presence of two subscribing 70 witnesses, Sept. 28th 1908.

ALFRED ERNST.
